UNITED STATES PATENT OFFICE.

REINHOLD HERMAN, OF CROFTON, PENNSYLVANIA.

SIGNAL MECHANISM.

SPECIFICATION forming part of Letters Patent No. 705,584, dated July 29, 1902.

Application filed October 25, 1901. Serial No. 79,977. (No model.)

To all whom it may concern:

Be it known that I, REINHOLD HERMAN, a citizen of the United States of America, residing at Crofton, in the county of Allegheny and State of Pennsylvania, have invented 5 certain new and useful Improvements in Signal Mechanism, of which the following is a specification, reference being had therein to the accompanying drawings.

10 This invention relates to certain new and useful improvements in signaling mechanism, and relates particularly to that class of signals employing track-circuits controlled by train movements for actuating the signal-operating mechanism to automatically move the signal from "clear" to "caution" or "cancion" to "clear" and "danger" positions.

15 The present invention relates to an improvement in the operating mechanism and 20 is applied to such operating mechanism as is shown in my Patent No. 683,397, dated September 24, 1901, and in order to clearly illustrate my invention I have shown a form of signal-operating mechanism such as is shown 25 and described in the above-mentioned patent.

25 The present invention relates to an improvement in the mode of operating the signal; and it consists in employing, in connection with the mechanism such as shown in 30 my Patent No. 683,397, a toothed sector in connection with a rack-bar to be engaged by said sector, the rack-bar being adjustably connected to an operating-rod which extends through the hollow support (not shown) for 35 the signal and connects to the latter. Instead of employing a yoke, as in my prior patent, and connecting this yoke to the signal-rod and to the sector and instead of having the lock-magnets actuate the mechanism 40 to engage directly with the sector to lock the signal in its respective positions I employ the rack-bar and lock directly into this rack-bar, the latter being arranged to move vertically in suitable rollers, which act as guides therefor.

45 The various parts employed in this improvement will be hereinafter more fully described, and specifically pointed out in the claims.

In describing the invention in detail reference is had to the accompanying drawings, forming a part of this specification, and where-

in like numerals of reference indicate corresponding parts throughout the several views, in which—

Figure 1 is a side elevation of a signal-operating mechanism such as described in detail in my Patent No. 683,397, showing my present improvements applied in position. Fig. 2 is a front elevation of the same. Fig. 3 is a detail front elevation of the rack-bar. Fig. 4 is a central vertical sectional view of one of the guide-rollers for the rack-bar, showing a part of the shaft upon which the roller is mounted.

As heretofore stated, the present apparatus 65 is adapted to be employed in connection with track-circuits such as are shown in my Patent No. 683,397, and in the present illustration of my invention I have shown parts of the operating mechanism which will not be described 70 herein in detail, as they are fully shown and described in my former patent. In my Patent No. 683,397 I employ a yoke, which is pivotally connected to the sector, and connect this yoke to the operating-rod, which is attached to the signal or semaphore arm. In the present invention this yoke is dispensed with, and the sector 1, which is mounted on the drive-shaft of the operating mechanism, is provided with teeth 2, which are adapted 80 to engage with teeth 3, formed on the front face of the vertically-disposed rack-bar 4. The clutch-magnets 2', which engage the drive-wheel 3' when the motor 4' is energized to cause the drive-shaft to operate the sector 85 1 and like parts of the mechanism, have been fully shown and described in my former patent. The standards 5 of the operating mechanism are provided at their upper ends with brackets 6, and in these brackets is mounted 90 a shaft 7. This shaft 7 has arranged thereon a guide-roller 8, which is held against endwise movement in any suitable manner, a preferable construction being by mounting collars 9 on the shaft at each end of the roller and securing the same by the cotter-pins 10. Each of the standards 5 is also provided with brackets 11, which project outwardly from the rear edge of the standards and have mounted thereon a shaft 12, which has mounted thereon a roller 8, the same as the roller at the upper end of the mechanism. The rack-

bar 4 is adapted to be connected to the rod 14, which is connected to the signal. (Not shown.) This connection is preferably a pivotal one, being made by means of a yoke 15 and pin 16, the latter passing through the rack-bar 4 near its upper end. The yoke carries a threaded stud 17, which engages into the sleeve 18, the upper end of said sleeve receiving the lower threaded end of the rod 14. This sleeve, together with the threads on the studs 17 on the end of the rod 14, is made right and left hand, so as to permit the adjustment to regulate the throw of the signal-arm in a manner well known in the art. The rack-bar 4 is provided with notches 19, suitably positioned to receive the locking-block 20 of the toggle mechanism 21, this toggle mechanism being operated by the lock-magnets 22, which are mounted in a frame or bracket connected to the bridge-plate 22' in a manner as has been fully described in my prior patent and pending applications. I have shown the bar 4 as provided with but two notches 19, the one for locking the signal in the clear position (the position shown) and the other notch to receive the locking-block for holding the signal in the caution position, the signal being automatically held in the danger position, though, of course, it will be observed that where desired the bar may be provided with an additional notch for locking the signal in the danger position, or it may be provided with as many notches as it may be desired to lock the signal in the different positions. Upon the mechanism being actuated by the energizing of the motor and the lock-magnets being deenergized, so as to release the locking-block, the sector in its movement elevates the rack-bar 4, so as to shift the signal to the caution or danger position, as the case may be, this rack-bar being guided by the rollers 7, and the pivotal connection between the rack-bar and the operating-rod 14 obviating any danger of the bending of the rod.

Having fully described my invention, what

I claim as new, and desire to secure by Letters Patent, is—

1. In electrically-operated signals, the combination with a pair of supporting-standards, a drive-shaft journaled therein, and a toothed sector carried by the drive-shaft, of a rack-bar engaged by the sector and operated thereby in a vertical line, a signal-operating rod to which the upper end of the rack-bar is attached, and a lock for engagement with the rack-bar to hold the same in the position to which it is moved by the sector, substantially as described.

2. In electrically-operated signals, the combination with a drive-shaft, and a toothed sector carried by the drive-shaft, of a signal-operating rod, a vertically-disposed rack-bar connected to the signal-operating rod and in continuous engagement with the sector, said sector when actuated moving said rack-bar and signal-operating rod in a vertical line, and means for direct locking engagement with the rack-bar to hold the latter and the signal-operating rod in the position to which they have been moved, substantially as described.

3. In signals, the combination with the supporting-standards, a drive-shaft journaled therein, and a toothed sector carried by said drive-shaft, of a signal-operating rod, a vertically-disposed rack-bar attached at its upper end to said rod and having notches in its rear face, said rack-bar in continuous engagement with the sector and moved thereby in a vertical line, means for guiding said rack-bar in its vertical movement, and a locking device for engagement with the notches in the rear face of said bar to hold the same in the position to which it has been shifted, substantially as described.

In testimony whereof I affix my signature in the presence of two witnesses.

REINHOLD HERMAN.
